UNITED STATES PATENT OFFICE.

THOMAS E. COLLINS, OF CHICAGO, ILLINOIS.

FIRE-SHUTTER.

1,242,658.

Specification of Letters Patent.

Patented Oct. 9, 1917.

Application filed June 28, 1916. Serial No. 106,310.

To all whom it may concern:

Be it known that I, THOMAS E. COLLINS, a citizen of the United States, residing at Chicago, in the county of Cook and State of Illinois, have invented a certain new and useful Improvement in Fire-Shutters, (Case 2,) of which the following is a full, clear, concise, and exact description, reference being had to the accompanying drawing, 10 forming a part of this specification.

My invention relates to automatic fire shutters.

The conditions of operation imposed upon devices of this class are severe. These devices are generally employed to guard openings, such as doorways and the like, so that a fire originating in one part of a building or in one room will not be communicated to another part or to another room. The shutter serves as an automatic closure of the doorway or the like upon the occurrence of fire conditions. The shutter must also function as a door to close off the doorway and to be readily operable to permit traffic 20 through the doorway. That is to say, during normal conditions the shutter must serve as a door and during fire conditions it must serve as an automatic closure.

Devices of this class generally consist of 30 a door or shutter element which may be operated normally as a door and a closing means which is normally inactive but which becomes active to positively close door or shutter element upon the occurrence of fire 35 conditions. Due to the necessity of using a powerful and positively acting closing means, the automatic shutter is exposed to various severe usage. This has been remedied to an extent by the application of 40 governing means for regulating the speed of closure. On some types of doors, the governing means is constantly connected to the shutter. It therefore is subject to continual wear by the ordinary usage of the device as a door and may to a certain extent lose its adjustment. It also makes the door 45 more difficult to operate.

Other devices have been proposed whereby the governing device is in the nature of a 50 spring or the like for counterbalancing or governing the closing means. This spring is normally disconnected from the shutter and becomes connected only upon the occurrence of fire condition. This type of govern- 55 er or controller has been found to be

unreliable as the spring tension varies and may inadvertently become changed or lost so that failure results. Furthermore, to be successful the door must always be in the same position when the automatic closing 60 means is applied, otherwise the spring tension of the governor would not be entirely effected.

The necessarily complicated nature of this type of brake or governor makes it expensive and generally undesirable in operation. The parts are hidden and difficult to reach for adjustment and inspection and it is difficult to determine the condition of the device. 70

My invention aims to provide a simple and efficient brake in combination with an automatically closing shutter which is free from the above objection and which is accessible and inexpensive and which is readily adjustable to secure different speeds of operation. 75

In the accompanying drawings in which I have illustrated one form of my invention— 80

Figure 1 is a front elevation with parts broken away of a fire shutter embodying my invention;

Fig. 2 is a left hand elevation of the same;

Fig. 3 is a right hand elevation of the 85 same on a slightly enlarged scale;

Fig. 4 is a front view of the mechanism shown in Fig. 3;

Fig. 5 is a fragmentary detail view of the cylinder and air port; and 90

Fig. 6 is a view taken at right angles to the same.

A shutter or curtain 1 (see Fig. 3) has its upper end attached to the drum 2, the major portion of the curtain being normally wound 95 upon the drum. The curtain 1 is composed of a number of metallic sections secured together in such manner as to permit the curtain to be wound upon the drum as described. The drum 2 is supported at the left end upon 100 a shaft 3 and at its right end upon a shaft 4, these two shafts being axially in line. A counterbalancing spring 5 is contained within the drum 2 and this spring has one end attached to the shaft 3 and the other end attached to the drum 2. The tension of the spring may be suitably adjusted by means of a plate 6 which is keyed to the shaft 3. The plate 6 is provided with a number of sockets 7 which are adapted to be engaged 110

by a suitable pin 8 passing through a bracket 9 and mounted upon the end plate 10 of the supporting housing. A similar end plate 11 (see Fig. 3) forms the other end 5 of the housing and the shafts 3 and 4 have suitable bearings in these end plates. The lateral walls of the housing are formed by a metal cover 12. The lower end of the curtain 1 is provided with a bar 13, the 10 ends of which bar project between the parallel sides of the angle bars 14 and 15 which form a groove for guiding the bar 13. An angle bar 16 is attached to the front of the bar 13 and a channel bar 17 is attached to 15 the rear of the bar 13. The outer end or flange of the channel bar 17 is adapted to engage the lintel 18 of the doorway. An iron bar 19 is normally suspended from a shaft 20 and is adapted under fire conditions, as will be described later, to be 20 dropped into the channel 17 to cause the curtain to be lowered. The bar 19 is provided with hooks 21 which engage arms 22 on the shaft 20 so that when the shaft 20 turns into the position shown in Fig. 3, the 25 bar 19 will be supported upon the shaft 20. A pair of cables 23 are supported from brackets 24 and these cables pass through the ends of the bar 19 forming guides therefor to prevent accidental displacement of 30 the bar 19.

The shaft 20 has bearings in the end plates 10 and 11. The left hand end of the shaft 20 has a weighted raising lever 25 secured thereto as by a pin or $\frac{1}{4}$. The lever 25 is normally held in the raised position, as shown in Figs. 1 and 2, by means of a controlling lever 26 which is formed in the shape of a bell crank and pivoted 40 to a plate 27 secured to the end plate 10. The horizontal arm of the bell crank 26 is adapted to be moved under the end of the weighted lever 25, the vertical arm of the bell crank 26 being held by a wire or cable 45 28 which includes a fusible link 29 in such position as to be subjected to any excessive rise of temperature, such as would occur in case of fire. The opposite end of the cable 28 is secured to the vertical arm of a bell 50 crank lever 31 which controls the connection of the governor to the drum. It is obvious that the cable 28, instead of being secured between the two controlling bell crank levers, may be connected through a 55 suitable abutment or stationary object, or may be so arranged as to release the two controlling levers at substantially the same time. It is also obvious that a single controlling lever may be employed to control 60 both devices without departing from my invention.

The governor which I employ is normally disconnected from the shutter mechanism so 65 that the shutter is free to be operated as a door without operating the governor.

There is thus a minimum of wear upon the governor. The curtain is not subject to the drag of a governor during normal operation. The shaft 4 which is connected to the drum 2 projects out through the end plate 11 and bears a gear 32 which is keyed 70 to the shaft 4. A weighted bell crank lever 33 having the longer arm 34 projecting outward from the wall in generally a horizontal direction, is pivoted at 35 to the end plate 11. The other end of the bell crank lever 33 bears a pin 36 which serves as a bearing for the pinion 37. The pinion 37 is preferably provided with a flange 38 formed integrally with the body of the 80 pinion to provide proper support for the wrist pin 40 which may be screwed into any one of the holes 41, 42 and 43. The purpose of the adjustment of the location of the crank pin 40 is to secure a greater or 85 less stroke. A suitable cylinder 44 is mounted upon the end plate 11 in a generally vertical direction in position to be operated by the pinion 37 when the same is rotated. The cylinder 44 is provided with a piston 45 mounted on the piston rod 46. The piston rod 46 extends completely through the cylinder, being guided by suitable bearings in the cylinder head at both ends. The piston rod is connected by a suitable wrist 90 pin 47 and pitman 48 to the pinion 37. The upper and lower cylinder heads are provided with vents or valves 49 and 50 which have ports therethrough, as shown in Figs. 5 and 6 controlled by suitable means such 95 as the set screws 51. The weighted arm of the bell crank 33 is normally in the raised position as shown in full lines in Fig. 3 and the pinion 37 is out of mesh with the gear 32. The controlling lever 31 is pivoted 100 on a plate 52 secured to the end plate 11. A swinging latch member 53 is pivoted to the bottom of the plate 52 and lies in such position that when the weighted arm 34 drops downwardly to put the gear 32 105 and the pinion 37 in mesh, the arm will be held in the downward position to prevent disengagement of the gears. A suitable stop or bracket 54 is provided to prevent excessive movement of the arm 34. It can 110 now be seen that when the fusible link 29 releases the end of the cable 28, the bell crank levers 26 and 31 will be free to permit the weighted levers 25 and 34, respectively, to drop. The weighted lever 25 in 115 dropping, causes the arms 22 on the shaft 20 to disengage the hooks 21 on the bar 19 so that the bar drops into the channel 17 thereby starting to lower the curtain 1. At the same time, the weighted arm 34, being released, throws the pinion 37 into engagement with the gears 32 so that the drum 120 is connected to the governor by the release of the thermal control. The air governor forms a dashpot or fluid brake which is 125 130

effective to secure a rapid but smooth descent of the curtain. As the curtain unwinds the effective diameter of the drum becomes less and due to the increase in speed the 5 governor becomes more effective.

This fluid brake is not to be confused with a friction brake as the operation of the two are totally different. The fluid brake prevents less friction to movement 10 for slow speed than it does for high speed, presenting practically zero resistance to start the same. In a friction brake, on the contrary, the friction is excessive just before starting and becomes less after movement 15 is initiated.

It is apparent that the fluid brake may be otherwise constructed and that the means for connecting the same operatively to the drum may be varied and I consider such 20 variations to be within the spirit and scope of my invention.

I claim:

1. In combination a flexible curtain, a drum for said curtain, means for lowering 25 said curtain, a gear connected to said drum, a pivoted arm, a pinion having a bearing on said arm, said pinion being adapted to mesh with said gear but being normally out of mesh therewith, a fluid dash-pot connected to said pinion to oppose rotation 30 thereof, and automatic thermally controlled means for moving said arm to cause the pinion to mesh with said gear, and latching means for holding said arm in position to 35 maintain said gear and said pinion in mesh.

2. In combination, a casing having a roller therein and a shutter wound on said roller, a weight to move the shutter, a restraining arm for the weight, a gear operable with said roller, a lever pivoted adjacent 40 said gear and carrying a pinion, a fluid brake connected with the pinion, fusible means to restrain said arm and lever, destruction of said fusible means permitting 45 the weight to actuate the shutter and allowing said lever to move said pinion into mesh

with the gear to connect the brake and retard movement of the shutter.

3. In combination, a drum having a flexible shutter wound thereupon, a weight to 50 cause descent of said curtain, a gear on said drum, a reciprocating fluid brake having a crank and connecting rod, a pinion associated therewith, a lever carrying said pinion, a restraining arm for said lever to 55 maintain said pinion out of engagement with said gear, means to suspend said weight, and fusible means extending between said weight suspending means and said lever, whereby upon destruction of the 60 fusible means said lever and said weight suspending means will be simultaneously actuated.

4. In combination, a casing, a roller mounted therein and a flexible shutter 65 wound on said roller, and a weight to lower the shutter, a restraining arm for the weight, a gear operable with said roller, a lever pivoted on said casing and carrying a 70 pinion, retarding means connected to the pinion, means to support said lever, and a fusible means extending between the weight arm and last said means.

5. In combination, a casing having a roller therein and a curtain wound on said 75 roller, a weight to lower the curtain, means to restrain the weight composed of an arm, a gear connected to the drum, a retarding device on the casing, an arm pivoted on the casing and having a pinion thereon operatively connected with the retarding device, fusible means extending between the weight 80 restraining means and said pivoted arm whereby when said fusible means is destroyed the curtain is permitted to lower 85 and the pivoted arm dropped bringing said pinion into engagement with the gear to retard the downward movement of the curtain.

In witness whereof, I hereunto subscribe 90 my name this 21st day of June A. D. 1916.

THOMAS E. COLLINS.
